UNITED STATES PATENT OFFICE.

JOSEPH H. MOSIER, OF PROVEMONT, MICHIGAN.

TWO-CYCLE ENGINE.

1,109,694.

Specification of Letters Patent. Patented Sept. 8, 1914.

Application filed November 11, 1911. Serial No. 659,694.

To all whom it may concern:

Be it known that I, JOSEPH H. MOSIER, a citizen of the United States, residing at Provenmont, in the county of Leelanau and State of Michigan, have invented a new and useful Improvement in Two-Cycle Engines, of which the following is a specification.

This invention relates to a two cycle internal combustion engine and relates especially to the arrangement of the cylinder ports, particularly the inlet ports, and the object of the invention is to increase the efficiency of the engine and develop a greater amount of power from a given charge by so arranging the ports that the incoming fresh charge does not mingle with the products of combustion, whereby the new charge is weakened, nor does any of the fresh charge escape through the exhaust opening.

A further object of the invention is to prevent back firing in the compression chamber through a delayed or late firing of the explosive mixture, such delayed or late firing being usually caused by too lean a mixture of the explosive gas, working upon the same principle as in a gun which hangs fire by reason of damp powder. In such case, as in the case of a lean mixture, a portion of the charge must first burn to produce enough heat to fire the full charge. In the case of an engine incoming gases come into contact with such a delayed combustion, and are ignited by it, thereby resulting in back firing. When the incoming gas is admitted at the top of the cylinder it does not come into immediate contact with burnt gas escaping at the exhaust port, which is always the hottest part of an engine in operation. Furthermore when gas is admitted into the top of the cylinder the gas is always pure around the spark plug thereby causing a quick, sure, powerful and complete explosion and this in turn prevents carbon deposits on the piston head. Such deposits when formed burn or are incandescent for a moment after each explosion, and after the incoming gas is admitted into the lower portion of the chamber it comes into contact with such burning deposit and is liable to become ignited prematurely thereby causing back firing.

In the accompanying drawings, Figure 1 is a central vertical section through the upper portion of the engine cylinder, the piston being at the end of the up stroke. Fig. 2 is a vertical section taken at right angles to that of Fig. 1 and showing the piston in

its lowest position. Fig. 3 is a cross section upon the line 3-3 of Fig. 1. Fig. 4 is a cross section upon the line 4-4 of Fig. 2.

In these drawings, 1 represents that portion of the engine cylinder in which works a piston 2 and into which an explosive mixture is introduced and ignited by means of a suitable ignition device 3. In the upper portion of said cylinder and upon opposite sides are arranged inlet ports 4 and below these ports and at a distance from them but somewhat less than the length of the piston 2 are intake ports 5, the ports 4 and 5 being connected upon opposite sides of the piston respectively by vertical passages 6. Arranged at right angles to the ports 5 and in a horizontal plane substantially the same as that of the lower edges of the ports 5 are exhaust openings 7. In a motor of small size one exhaust port would be sufficient but in a larger engine such as I have illustrated it is preferable to provide two of these exhaust ports upon opposite sides of the cylinder, but they are connected to a common exhaust outlet 8 by means of suitable passages 9, which passages are inclined slightly downward in order to bring the exhaust outlet 8 below the plane of the port 5 upon that side of the cylinder, as shown most clearly in Fig. 1.

The piston 2 is provided with upwardly and outwardly extending lips 10 upon the sides adjacent the ports 4 and through or immediately beneath said lips the piston head is provided with passages 11, which are adapted to place the ports 4 into communication with the interior of the hollow piston, and also with the lower portion of the cylinder when the lips 10 are above said ports, as shown in Fig. 1.

The operation of the engine is as follows: Assuming that the parts are in the position occupied in Fig. 2, that is the piston head is in its lowest position; the passages 11 are in communication with the ports 5, and the explosive mixture which is introduced into the lowest portion of the engine cylinder by any desired means, not shown, passes through the ports 11 into the ports 5, through the passages 6 and ports 4 into the upper portion of explosion chamber of the cylinder 1. Upon the up stroke of the piston the said charge is compressed and it will be noted that at no time during the admission or compression of the said charge has it been admitted directly to that portion of the cylinder in communication with the exhaust

ports 7. The charge is then fired and as a result of the explosion the piston is moved downwardly, the lower portion of the piston at the time of the explosion covering the ports 5. When the piston reaches its lowest point of travel it uncovers the exhaust ports and at the same time brings the passages 11 into communication again with the ports 5, the lips 10 acting as shields between the ports 5 and the exhaust passages. The burned gases therefore pass out through said exhaust passages as the new charge is admitted through the passages 11 of the piston head, and there is at no time any possibility of commingling of the burned products in the new charge being taken in.

What I claim is:—

1. In an internal combustion engine, a cylinder having intake ports arranged upon opposite sides thereof, inlet ports in vertical alinement with said intake ports, each inlet port having communication with one of the intake ports through a longitudinal passage, said cylinder having an exhaust port out of horizontal and vertical alinement with the intake ports, and a piston provided upon opposite sides with upwardly and outwardly extending lips, said piston being hollow and downwardly open, and having passages in said lips, said passages being adapted to register with the intake ports, and the said piston covering the exhaust port during the entire time that said lips cover the inlet ports, the piston uncovering the exhaust port only during the time that said lips register with the intake ports.
2. In an internal combustion engine, a cylinder, igniting means arranged in one end of the cylinder, inlet ports formed in oppo-

site sides of the cylinder and adjacent the ignition device, a set of intake ports arranged in longitudinal alinement with the ports first mentioned, longitudinally extending passages connecting the intake and inlet ports respectively, an exhaust port off-set with respect to the intake ports, a hollow piston open at one end and having upwardly extending lips upon the end adjacent the ignition device, and having passages through said lips, the said lips being adapted to cover alternately the intake and inlet ports, the passages registering with said ports, and said piston being of such length that the exhaust port will be covered during the time that said lips cover the inlet ports, said lips covering the intake ports during the entire time that the exhaust port is open.

3. An internal combustion engine comprising a cylinder open at one end and having an ignition device at its inner end, and having inlet ports discharging directly into said inner end portion of the cylinder and adjacent said ignition device, the said cylinder having also ports having free communication through longitudinal passages with the first mentioned ports, said cylinder having also an exhaust port adjacent the said second mentioned ports, and a piston provided with lips adapted to cover the first and second mentioned ports alternately, said lips having passages therethrough adapted to be brought into alinement with said ports as the lips pass by them.
